UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, A CORPORATION OF MASSACHUSETTS.

METHOD OF METAL-DRAWING.

1,295,430.

Specification of Letters Patent. Patented Feb. 25, 1919.

Application filed October 24, 1917, Serial No. 198,326. Renewed January 14, 1919. Serial No. 271,162.

To all whom it may concern:

Be it known that I, HJALMAR G. CARLSON, a citizen of the United States, residing at Worcester, in the county of Worcester and 5 State of Massachusetts, have invented a new and useful Method of Metal-Drawing, of which the following is a specification.

This invention is an improvement over my prior Patent No. 1,200,309, patented October 10 3, 1916, and relates, as that does, to a method of producing a hollow article of sheet metal such as a shell or booster casing which may be used for many purposes in accordance with its particular size and shape. A characteristic feature of the article, however, 15 is that it varies in thickness from its closed end to its open end, being thicker at the open end, and cylindrical inside but conical outside. Also it may have in addition 20 an integral enlargement at its open end formed by a thickening process instead of being doubled over or creased, so that it has no internal seam.

The principal objects of this invention 25 are to provide a method of producing an article such as above described, but of superior character and with the employment of comparatively little power, and particularly to provide means whereby by a simple drawing 30 operation the interior of a shell-shaped article can be left in a uniform and smooth condition, and an article finally shaped up to the desired definite shape.

Reference is to be had to the accompanying 35 drawings, in which—

Figure 1 is a transverse sectional view of a die showing a plunger in the act of performing the first operation;

Fig. 2 is a similar view showing the second 40 operation;

Fig. 3 is a sectional view of a different form of die and a plunger showing the operation of reducing the thickness of the end of the blank;

45 Figs. 4, 5 and 6 are views similar to Figs. 1 and 2 showing three other specific steps of the method as set forth in my above mentioned patent.

Fig. 7 is a similar view showing the first 50 additional step of the new method;

Fig. 8 is a similar view showing the next step in which the stripping of the blank from the plunger also assists in shaping it;

Fig. 9 is a similar view showing the thickening of the edge;

Fig. 10 is a similar view showing the completion of this step, and

Fig. 11 is a side view of the completed article.

This invention like my above mentioned 60 patent is designed for the production of the shell having a cylindrical surface inside, provided with a closed end and an open end, and having the metal thicker at its open end than at its closed end and growing so 65 progressively from one end to the other.

I have discovered, however, that I can materially improve the product of that method, as well as reduce the amount of power required for it, by adding a double 70 operation. This consists in drawing the metal out on a conical plunger, larger at the end than at the top. This allows the thickened top part of the blank to conform itself to the plunger. Then the blank is 75 stripped forcibly off the plunger which in itself further smooths the inside of the blank and shapes it to a true cylindrical form.

Referring now to the drawings, the first 80 step in the preferred process is to take a flat blank and place it on top of a die 10 which has a perforation or opening 11 of a shape corresponding with the shape of the desired article, in this case circular. This opening also is smaller than the diameter of 85 the flat blank which is to be operated upon. This flat blank is forced into the die and preferably through it by a plunger 12 which is cylindrical in form or at any rate uniform from end to end. The result of this 90 operation is to draw the metal of the blank so as to elongate it and to hold in the outer edge of the blank so that this edge is slightly thickened.

The cup-shaped blank *a* having been produced in accordance with the arrangement shown in Fig. 1, it is then placed in a second die 20 and forced through it by a cylindrical plunger 22. The blank *a'* is produced having a further elongation and smaller diameter and its edge is thickened still further. It is found in practice that this thickening extends substantially from the open to the closed end of the blank so that the blank may be considered as having a conical inner 100 surface, although it is not a perfect cone. The blank is thereafter subjected to a succession of these operations in a series of dies and plungers all having the same relation to each other, as has been described, and a 110

series of blanks α^2 , α^3 , and α^4 is obtained, each one smaller and longer than the one from which it is made and thicker at its open edge. The dies and plungers operating 5 on the blanks α^2 , α^3 , and α^4 are designated respectively 30, 40, 50 and 32, 42 and 52 all these plungers being shown as cylindrical.

At an intermediate point in this process, preferably after the operation shown in Fig. 10 2, and before that shown in Fig. 4, the closed end of the blank is flattened and thinned by subjecting the blank to pressure between a flat bottomed die 23 and a plunger also having a flat bottom. This plunger may be if 15 desired made of exactly the same shape and size as the plunger 22 and may in fact be the same one as indicated. If desired, the die 23 can be located just below the die 20 and receive the plunger and blank as soon as the 20 latter is freed from the die 20 by passing entirely through it.

It will be understood that the number of operations above described will depend upon the article being produced and the metal of 25 which it is produced and that this method is not limited to any particular number of such operations.

After the blank has been brought to the condition shown at α^4 in which it is of substantially the diameter and length desired, the rough, thickened open end is squared off by any desired means, and then it is put through the operation shown in Fig. 7. In Fig. 7 it is shown as being forced into a die 35 53, which instead of having a cylindrical passage therethrough, is provided with a cavity having two cylindrical portions 54 and 56 and a double convex portion 55 of different sizes. The blank is forced into this 40 die by a plunger 57 which is conical with the larger diameter at the end and it has a shoulder 58.

This die 54—55—56 is supported on a die bed 59 having a central hole into which the blank can be forced and supporting two stationary rods 60 having springs 61 that carry upon them a stripping plate 62 supported by the springs. Nuts or other stops 63 are provided for preventing the rise of the stripping plate above a certain position. The 50 stripping plate is provided with a stripper 64 through which the plunger 57 passes and which substantially fits the upper cylindrical non-working part of the plunger. This 55 plunger is carried by a punch block 65 that reciprocates in a well known manner. It is to be noted that the plunger is vented by a perforation 66.

In operation the blank α^4 is registered with the plunger when the latter is in its highest position and can be held by the hand while the plunger comes down and takes the blank down through the die 54, 55 and 56. The double convex part 55 of this 65 die is the part that does the work and is an

important feature because it provides clearance below and gradually slopes away from the operating surface in both directions. This, of course, is a true drawing operation. The result of this operation, as shown in Fig. 7, is to again thicken the metal at the top and force it in against the conical plunger all along its surface leaving the blank α^5 conical inside and cylindrical outside.

After the blank is thus formed up into the shape indicated at α^5 the plunger is drawn back through the same die surface 55. It will be seen now that by giving this die surface its double curved shape a true drawing operation can be performed as the plunger is withdrawn. Inasmuch as the blank has been forced back against the conical plunger in the previous operation the plunger will securely hold the blank while it is being drawn up through this die and the die 85 will tend further to smooth its surface. When the plunger is withdrawn to the position indicated in Fig. 8 the edge of the blank comes against the stripper 64 and then the plunger is withdrawn from the blank by 90 force. This necessarily brings the inside of the blank to a true cylindrical shape and forces the metal out on the previously smoothed outside into a conical shape again.

The withdrawal of the plunger 57 constitutes another step of the process because the gradually thickening plunger necessarily forces the metal out and smooths the inside leaving it truly cylindrical. This again leaves the shell α^6 conical outside.

The next operation shown in Figs. 9 and 10 consists in forcing the blank into a die 70 having a conical surface 71 and an enlarged cylindrical surface 72. This is done by means of a plunger 73 of cylindrical form throughout. The die 70 is supported in a stationary die bed and above it is supported by springs 74 on rods 75 a plate 76 which carries a die 77 through which the plunger 73 is adapted to be forced. This plunger 73 has a shoulder 78 at its top on which rests a plate 79 located in a well in a die head 80 and pressed down by a heavy spring 81. This gives the plunger power of motion independent of the die head 80 which is operated positively. The lower part of the die 77 is cylindrical to fit in the cylindrical surface 72 of the die. The operation of this mechanism is as follows:

When the punch is moved up and the die 77 has followed it on account of the action of the springs 74 the blank α^6 previously described is put on the plunger as just described. Then the die head 80 comes down and forces the blank α^6 into the conical recess 71 which exactly fits it. The outside of the plunger 73 also exactly fits the inside cylindrical surface of the blank α^6 . Consequently below the enlargement 72 of the die no shaping operation takes place here, but

the plunger 73 is held down by heavy spring pressure due to the spring 81 and thus prevents the action of the die 77 buckling the metal in any way or forcing the metal under 5 the plunger so as to raise it. As the parts move down the projection 82 on the die head forces the plate 76 down and the die 77 into the opening 72 and tends to consolidate the shouldered end edge of the blank and finally 10 brings it into the form α' shown in Fig. 10.

It is to be noted that the die 70 is provided with a vent 84 at the bottom and with a side vent 85 at the top. Also that the plunger is provided with a vent 86 connected with a 15 longitudinal vent 87 to allow the air to escape. This is an important matter because the parts fit so tightly that otherwise the air originally present on both sides of the edge of the blank would tend to cause irregularities 20 in the product or split the dies. By this venting action both difficulties are entirely avoided and the blank comes out in the form shown at α' . By this series of operations a blank is produced which is not only cylindrical and conical as stated, but in which 25 these cylindrical and conical surfaces are smooth and perfect and the amount of power required even in my above mentioned patent to produce an inferior article is materially 30 reduced, while the possibility of splitting the dies is entirely removed and the expense of the machine which has been thought necessary heretofore is reduced to a very small maximum. The result of this operation is 35 to finish the shell α' so as to retain its complete true cylindrical inner surface, give it a true conical outer surface, and shape its enlarged cylindrical shoulder at the top having a square end. Upon being removed from 40 this die and plunger, the shell is ready for any machining operations such as providing the screw-threads, on the shoulder of the shell α' .

In this way an article is secured having a 45 maximum strength and of a maximum degree of perfection throughout, and yet the method of producing it is so extremely expeditious that when a large number of articles are to be produced it can be done in a 50 most inexpensive manner and without the use of much power.

Although I have illustrated and described a certain number and sequence of steps and shown the method as applied to the production 55 of a specified article, I am aware of the fact that the invention is not limited to these respects and therefore I do not wish to be so limited except as set forth in the claims.

Having described the invention what I 60 claim is:—

1. The method of drawing metal which comprises forcing a blank through a die by means of a plunger larger at its tip than at its butt end, thus leaving a space between the

die and plunger around the latter greater 65 than the original thickness of the metal, whereby the metal throughout its length will buckle upon itself and thicken but will be shaped and drawn out between the die and plunger. 70

2. The method of drawing out and upsetting a cup-shaped blank, which comprises forcing the cup-shaped blank through a die by means of a conical plunger so as to cause the metal to buckle on itself and thicken, 75 causing the metal to remain in contact with and be shaped by the plunger all along the same so as to draw the thickened metal out to a thickness greater than its original thickness at that region. 80

3. The method of drawing metal which comprises forcing a blank through a die by means of a conical plunger, leaving a space between the die and plunger around the latter greater than the original thickness of the 85 metal, whereby the metal for a distance from its open edge will buckle upon itself and thicken but will be shaped and drawn out between the die and plunger, and thereafter drawing the plunger out to shape the metal 90 inside to a smooth uniform cylindrical form from end to end. 95

4. The method of drawing metal which consists in placing a cup-shaped blank against a die having a circular passage therethrough smaller than the diameter of said blank, forcing a plunger into the blank so as to bear on the inside of its closed end to force the blank through the die, for the purpose of elongating the blank, reducing its 100 outside diameter and thickening its open edge, and shaping the interior of the blank by means of the tip of the plunger.

5. The method of drawing metal which consists in forcing a blank into a die having 105 a passage therethrough smaller than the blank by means of a cylindrical plunger having substantially the same shape as said passage but small enough to permit the edge of the blank to thicken when in the die, 110 and thereafter subjecting the said blank to a further drawing operation in a die smaller than the blank as it comes out of the first die to permit the edge of the blank to thicken, whereby the blank is formed of uniform 115 outside shape from end to end but its inside diameter at the closed end is greater than it is at its open end, and stripping the plunger from the blank, thus shaping it to uniform inside the diameter at its open end. 120

6. The method of drawing metal which consists in forming by drawing operations a cup-shaped blank of cylindrical external form and roughly conical inside with a closed relatively thin end, forcing it through a die of smaller diameter than the blank by means of a plunger large enough at its tip to fill the blank as drawn through said 125

die and growing progressively smaller toward its butt end to furnish room to receive the thickened metal of the blank, and then stripping the plunger from the blank to 5 shape and smooth its inside surface.

7. The method of drawing metal which consists in drawing out a cup-shaped blank on a plunger to a form in which it is cylindrical outside and conical inside with its 10 open end having a smaller inside diameter than its closed end and then bringing its interior to a uniform diameter.

8. The method of drawing metal which consists in drawing out a cup-shaped blank 15 on a plunger to a form in which it is cylindrical outside and conical inside with its open end having a smaller inside diameter and a greater thickness of metal than its closed end, and then drawing the plunger 20 out through the small end to bring the inside to a cylindrical form with its open end thicker than its closed end.

9. The method of drawing metal which consists in drawing out a cup-shaped blank 25 on a plunger so as to force the metal against the plunger substantially throughout the length of the blank thus bringing the blank to a form in which it is cylindrical outside and conical inside with its open end having 30 a smaller inside diameter than its closed end, then drawing the plunger out through the small end to bring the inside to a cylindrical form, but leaving the edge of the blank larger than the main part, then holding the 35 inside and outside surfaces of the blank under high pressure throughout its main part to prevent any change in shape and compressing said larger edge.

10. The method of drawing metal which 40 consists in drawing out a cup-shaped blank on a plunger so as to force the metal against the plunger substantially throughout the length of the blank thus bringing the blank to a form in which it is cylindrical outside and conical inside with its open end having a smaller inside diameter than its closed end, and then drawing the plunger out through the small end to bring the inside to a cylindrical form, but leaving the edge of the blank of larger diameter than the rest of it, then forcing it into a die having the exact shape and size of the blank by means of a plunger fitting the interior of the blank,

holding the plunger in position under pressure and compressing the edge of the blank. 55

11. The method of drawing metal which consists in drawing out a cup-shaped blank on a plunger so as to force the metal against the plunger substantially throughout the length of the blank thus bringing the 60 blank to a form in which it is cylindrical outside and conical inside with its open end having a smaller inside diameter than its closed end, then drawing the plunger out through the small end to bring the inside to 65 a cylindrical form, but leaving the edge of the blank larger than the main part, then holding the inside and outside surfaces of the blank under high pressure throughout its main part to prevent any change in shape, 70 compressing said larger edge, and venting the external surfaces of the blank.

12. The method of drawing metal which consists in drawing out a blank to a cylindrical form outside and conical inside, its 75 open end having a smaller inside diameter and of greater thickness than its closed end, then drawing the plunger on which it is made out through the smaller end to bring the inside to a cylindrical form, but leaving 80 the edge of the blank larger and thicker than the main part, then holding the inside and outside surfaces of the blank under pressure throughout its main part to prevent any change in shape, and longitudinally compressing said larger edge. 85

13. The combination with a circular die, of a plunger coöperating therewith of conical form throughout its operative length with its large end at the tip. 90

14. The combination with a female die, of a plunger coöperating therewith having its large end at the tip, said die having a continuous double convex curve constituting the operating surface.

15. The combination with a female die having a double curved operating surface, of a spring supported stripping plate, and a positively operated plunger largest at its tip and gradually growing smaller toward its 10 other end and passing through said stripping plate into said die.

In testimony whereof I have hereunto affixed my signature.

HJALMAR G. CARLSON.
